LIQUID LEVEL GAUGE HEAD OR SIMILAR ARTICLE

Robert W. Morgan, Warren W. Hastings, and Clarence A. Mass, Rochester, N. Y., assignors to Rochester Manufacturing Company, Inc., Rochester, N. Y., a corporation of New York

Application November 14, 1956, Serial No. 43,757

Term of patent 14 years

(Cl. D52—1)

Fig. 1 is a front elevation of a liquid level gauge head or similar article, showing our new design; and

Fig. 2 is a side elevation thereof.

We claim:

The ornamental design for a liquid level gauge head or similar article, as shown.
